R. H. TUCKER

APPARATUS FOR EJECTING FLUIDS FROM WELLS

Filed June 1, 1922

UNITED STATES PATENT OFFICE.

RALPH H. TUCKER, OF LOS ANGELES, CALIFORNIA.

APPARATUS FOR EJECTING FLUIDS FROM WELLS.

Application filed June 1, 1922. Serial No. 565,132.

To all whom it may concern:

Be it known that I, RALPH H. TUCKER, a citizen of the United States, residing at Los Angeles, in the county of Los Angeles and 5 State of California, have invented new and useful Improvements in Apparatus for Ejecting Fluids from Wells, of which the following is a specification.

This invention relates to pumping apparatus and has for its object to provide a pneumatically operated plunger pump.

The present invention consists of a pumping apparatus in which there is provided a stationary foot section having a stationary 10 upwardly extending sleeve. Upon this sleeve there is slidably fitted a piston operating in the stationary pump foot section. Means are provided for forcing compressed air down into the center sleeve and guide 15 upon which the piston slides so that an accumulated air pressure serves to act as a piston for lifting the plunger member in the foot section. Means are also provided for releasing the accumulated air pressure 20 after the pump plunger has reached a predetermined point in its upward liquid lifting stroke.

Other objects will be made manifest in the following specification of an embodiment of the invention illustrated in the accompanying drawings, in which—

Figure 1 is a vertical central section through a form of the pump.

Fig. 2 is a section on line 2—2 of Fig. 1. 35 The present pump is shown as of the type adapted to be lowered into the bottom of a well hole W in which there is arranged the outer casing C which is perforated as at 2 at its lower portion for the reception of 40 well liquid.

Substantially concentrically spaced within the casing C is a pump tubing 3 of any suitable number of sections, and this is provided with a foot section 4 at its lower end, 45 the foot section being connected to the upper sections as by a suitable coupling 5 of differential diameters; the foot section being somewhat smaller in diameter than the upper sections 3, of which the lower part of 50 only one is shown.

The foot section 4 is provided with a substantial shoe 6 closing the lower section 4 and carrying on its lower face a screen 7 of any suitable construction for admitting the 55 well liquid. The shoe 6 is provided with a series of valve seats 8 upon which rest up-

wardly opening valves 9 of any suitable construction and design. Co-axially arranged upon the shoe 6 is an air pressure column 10 of suitable diameter and which extends a desired height upwardly from the shoe. Surrounding the air column 10 is a sleeve 11 having a transverse head 12 from which extends upwardly a short reduced stem 13. The head or shoulder 12 of the sleeve 11 is normally forced down toward the upper open end of the column 10 by an expansion spring 14, the upper end of which engages a suitable support as a gland nut 15 threaded into the contiguous end of an air pipe 16, to the lower end of which is secured a spider 16^a, the rim of which is of such diameter as to slide freely down through the pump tube 3 and rest upon the upper end of the pump foot section 4. The lower end of the spring rests upon the upper face of the head 12.

The sleeve 11 slidably and snugly fits upon the column 10 and carries a piston-like flange 17 having a cylindrical wall 18 about which is disposed suitable packing means 19 slidably bearing upon the lower inner surface of the foot section 4. Therefore, the cylindrical wall 18 with its sleeve 10 and its stem 13 forms a substantially 85 unitary or integral device operating in the nature of a piston or plunger.

Upon the diametrical wall or flange 17 of the plunger there is seated a suitable number of desirable upwardly opening 90 check valves 20.

The pipe 16 is constructed of any suitable number of sections and serves as a conduit for compressed air which, when forced downwardly therethrough, enters the tubular stem 13 and the stationary compression chamber or column 10 in which the pressure of the air reacts as a piston upon the piston part 12 of the plunger device and as the accumulated pressure overcomes the pressure of the column of liquid in the pump tube 3 the plunger is bodily lifted against the reaction of the spring 14 and the sustained column of liquid is moved upwardly and discharged from the outlet at the head of the pump. During the upward movement of the plunger head 17, the tendency to vacuumize the chamber above the shoe 6 causes the opening of the valves 9 and the inflow of fluid into the plunger chamber below the head 17.

A feature of the invention is that as well

as providing a pneumatically operative pump plunger, further, air is intermittently discharged into the column of fluid in the pump tube 3, and this air facilitates in rendering the liquid buoyant and accelerates the discharge by virtue of displacement. To that end, the sleeve 11 of the plunger is provided with suitable means for releasing the compressed air in the air column 10 5 when the plunger device has reached a predetermined position in its ascent. A form of air releasing means is shown as comprising a series of radially arranged outlets 21 in the sleeve 11, and these outlets 10 are provided with upturned ends carrying check valves 22. When the outlets 21 are shifted upwardly, as to the end of the column 10, then the air compressed therein is permitted to escape outwardly through 15 the check valves 22 and will enter and come into the column of liquid in the well tube 3.

Since the plunger device is elevated through the instrumentality of compressed air, it will be clear that as soon as the relief valves or outlets 21 communicate with the compressed air in the column 10, then the pressure of the air will instantly fall and the plunger will start its descent which, 20 under the load of the liquid in the pump tube and by the reaction of the spring 14, will cause the plunger to return to its lower-most position until air pressure is again built up after the outlets and valves 22 have 25 been shifted down to cut off the escape of air.

The pump plunger stem 13 is guided at its upper end in the air pipe 13, and when it is desired to remove the pump plunger 40 from the well, the air pipe 16 is lifted until it brings the packing seat 16' therein up against a collar 18' on the upper end of the stem 13. Thereafter, further upward pulling of the air pipe 16 serves to carry with 45 the pipe the spider 7 and the plunger device leaving the foot section 4 in its stationary position in the well casing.

Various modifications and changes may 50 be resorted to within the spirit of the invention as claimed.

What is claimed is:

1. A pneumatically operated plunger pump consisting of a stationary pump tube having a foot section provided with inlet valves in its lower portion, a stationary compressed air column fixed to the foot section, an air pressure pipe arranged in the pump tube, a piston-like plunger operatively fitting the foot section and having 55 communication with the air pipe whereby compressed air may be delivered from the pipe into said column whereby its pressure is operative as a piston upon the plunger to lift the same, and automatic air exhaust valves carried by the plunger. 60

2. A pneumatically operated plunger pump consisting of a stationary pump tube having a foot section provided with inlet valves in its lower portion, a stationary compressed air column fixed to the foot 70 section, a stationary air pressure pipe arranged in and extending nearly to the bottom of the pump tube, a piston-like plunger operatively fitting the foot section and having communication with and sliding in the air pipe whereby compressed air may be delivered from the pipe into said column whereby its pressure is operative as a piston upon the plunger to lift the same, and means for intermittently releasing air from the compressed air chamber in the apparatus into the liquid in the pump tube. 75

3. A pneumatically operative plunger pump comprising a stationary inlet valved means including a pump tube to be arranged in a well hole, a plunger valved device operative within said tube by pneumatic pressure created therein and through which well fluid passes, and means for intermittently discharging air from said 80 means into the pump tube. 85

4. A pneumatically operative plunger pump consisting of a pump tube having a valved inlet means at its foot, a compressed air column fixed to the foot of the tube, an air supply pipe extending down into the tube and spaced above said column, a plunger device slidably fitting said column and having a part slidably fitting in the air supply pipe and providing for communication between said pipe and said column wherein compressed air acts as a piston upon said plunger device to shift the same in one direction for elevating liquid in the pump tube and an air exhaust means for 100 discharging the air column. 105

5. A pneumatically operative plunger pump consisting of a pump tube having a valved inlet means at its foot, a compressed air column fixed to the foot of the tube, an air supply pipe extending down into the tube and spaced above said column, a plunger device slidably fitting said column and having a part slidably fitting in the air supply pipe and providing for communication between said pipe and said column wherein compressed air acts as a piston upon said plunger device to shift the same in one direction for elevating liquid in the pump tube, and means operative during the relative movement of said plunger device and the air pressure column for intermittently discharging air into the liquid in the pump tube. 110 115

6. A pneumatically operative plunger pump consisting of a pump tube having a valved inlet means at its foot, a compressed air column fixed to the foot of the tube, an air supply pipe extending down into the tube and spaced above said column, a plunger 120 125

- er device slidably fitting said column and having a part slidably fitting in the air supply pipe and providing for communication between said pipe and said column 5 wherein compressed air acts as a piston upon said plunger device to shift the same in one direction for elevating liquid in the pump tube, and means operative during the relative movement of said plunger device and 10 the air pressure column for intermittently discharging air into the liquid in the pump tube, said means comprising air outlets arranged on the plunger device and which are designed to be uncovered by the upward 15 movement thereof with respect to the air column.
7. A pneumatically operative plunger pump consisting of a pump tube having a valved inlet means at its foot, a compressed air column fixed to the foot of the tube, an air supply pipe extending down into the tube and spaced above said column, a plunger device slidably fitting said column and having a part slidably fitting in the air 20 supply pipe and providing for communication between said pipe and said column wherein compressed air acts as a piston upon said plunger device to shift the same in one direction for elevating liquid in the pump 25 tube, means operative during the relative movement of said plunger device and the air pressure column for intermittently discharging air into the liquid in the pump tube, and means for returning the pump plunger 30 to its lower position.
8. A pneumatically operative plunger pump consisting of a pump tube having a valved inlet means at its foot, a compressed air column fixed to the foot of the tube, an air supply pipe extending down into the tube and spaced above said column, a plunger device slidably fitting said column and having a part slidably fitting in the air supply pipe and providing for communication 35 between said pipe and said column wherein compressed air acts as a piston upon said plunger device to shift the same in one direction for elevating liquid in the pump tube, means operative during the relative 40 movement of said plunger device and the air pressure column for intermittently discharging air into the liquid in the pump tube, and a spring for returning the pump plunger to its lower position.
- 55 9. A pneumatically operative plunger pump consisting of a stationary pump tube having a foot section provided with inlet valves, said foot section having a central, upwardly extending column; a stationary air pressure pipe extending down in the pump tube; a piston-like plunger operatively fitting the foot section and having a portion slidably fitting the said column, an operating connection between the lower end 60 of the stationary air pipe and said plunger 65 whereby air is conveyed down to the air column, and means for discharging the compressed air from the column.
10. A pneumatically operative plunger pump including a stationary pump tube having a foot section with inlet valves, a stationary air supplying means extending down in the pump tube and nearly to the bottom thereof; an air column fixed to the foot section; a plunger device surrounding said column and operating on the same and having a packed running fit with the tube; an operating means connecting the stationary air pipe and the air column to supply air to the latter and which is connected to the plunger to operate the latter; and means for exhausting the compressed air at the upper stroke of the plunger. 70
11. A pneumatically operative plunger pump including a stationary pump tube having a foot section with inlet valves; a stationary air supplying means extending down in the pump tube and nearly to the bottom thereof; an air column fixed to the foot section; a plunger device surrounding said column and operating on the same and having a packed running fit with the tube; an operating means connecting the stationary air pipe and the air column to supply air to the latter, said connecting means including a piston-like part upon which the compressed air in the column reacts, and which is connected to the plunger to operate the latter; and means for exhausting the compressed air at the upper stroke of the plunger. 75
12. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger. 80
13. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger; said supplying means including a stationary air pipe extending down into the tube and an operating tubular connection communicating with the said column. 85
14. A pneumatically operative plunger 90
15. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger; said supplying means including a stationary air pipe extending down into the tube and an operating tubular connection communicating with the said column. 95
16. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger. 100
17. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger. 105
18. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger. 110
19. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger. 115
20. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger. 120
21. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger; said supplying means including a stationary air pipe extending down into the tube and an operating tubular connection communicating with the said column. 125
22. A pneumatically operative plunger pump including a stationary pump tube having an inlet-valved foot section; a stationary compressed air column; a piston-like plunger operatively fitting the foot section and being provided with upwardly opening valves for the passage of well fluid on the downward stroke of the plunger; means for supplying compressed air to said column to operate the plunger; and means for exhausting air from the column at the end of the upward stroke of the plunger; said supplying means including a stationary air pipe extending down into the tube and an operating tubular connection communicating with the said column. 130

5 pump including a stationary pump tube having an inlet-valved foot section; a stationary compressed air column; a piston-like plunger operatively fitting the foot section
5 and being provided with upwardly opening valves for the passage of well fluid on the downward stroke of the plunger; means for supplying compressed air to said column to operate the plunger; and means for exhaust-
10 ing air from the column at the end of the upward stroke of the plunger; said supplying means including a stationary air pipe extending down into the tube and an operating tubular connection communicating
15 with the said column and being connected to the piston-like plunger.

15. A pneumatically operative plunger pump including a stationary pump tube having an inlet-valved foot section; a stationary compressed air column; a piston-like plunger operatively fitting the foot section and being provided with upwardly opening valves for the passage of well fluid on the downwarl stroke of the plunger; means for
25 supplying compressed air to said column to operate the plunger; and means for exhausting air from the column at the end of the upward stroke of the plunger; said air supplying means including a stationary air pipe extending down into the pump tube and ending near the bottom thereof, and
30 having a sliding extension fitting the column and forming communication between the column and the pipe, and being connect-
35 ed to the plunger.

16. A pneumatically operative plunger pump including a stationary tube having an inlet-valved foot section; a stationary air column forming a pneumatic cylinder fixed in the bottom of the column, a plunger slid- 40 ably fitting the column and the tube, a stationary air pipe extending down into the tube and terminating above the said column, a conduit slidably mounted in the lower end of said pipe and communicating 45 with the stationary column and being connected to the plunger, and means for exhausting air from the column at the upper limit of movement of the plunger.

17. A pneumatically operative plunger 50 pump including a stationary tube having an inlet-valved foot section, a stationary air column forming a pneumatic cylinder fixed in the bottom of the column, a plunger slid- ably fitting the column and the tube, a stationary air pipe extending down into the tube and terminating above the said column, a conduit slidably mounted in the lower end of said pipe and communicating 55 with the stationary column and being connected to the plunger, and means for exhausting air from the column at the upper limit of movement of the plunger, said conduit providing a connection with the air pipe whereby the plunger can be pulled from 60 the tube when the air pipe is pulled.

In testimony whereof I have signed my name to this specification.

RALPH H. TUCKER.
